E. W. LA PLANT & R. E. CHOATE,
STUMP PULLER,
APPLICATION FILED SEPT. 4, 1917.

1,281,033.

Patented Oct. 8, 1918.

UNITED STATES PATENT OFFICE.

EDWARD W. LA PLANT AND ROY E. CHOATE, OF CEDAR RAPIDS, IOWA.

STUMP-PULLER.

1,281,033.

Specification of Letters Patent.

Patented Oct. 8, 1918.

Application filed September 4, 1917. Serial No. 189,436.

To all whom it may concern:

Be it known that we, EDWARD W. LA PLANT and ROY E. CHOATE, citizens of the United States, residing at Cedar Rapids, in 5 the county of Linn and State of Iowa, have invented certain new and useful Improvements in Stump-Pullers; and we do hereby declare the following to be a full, clear, and exact description of the invention, such as 10 will enable others skilled in the art to which it appertains to make and use the same.

The object of this invention is to produce a convenient and powerful portable stump-puller, the invention consisting in the construction, combination and arrangement of parts, as will be hereinafter fully set forth and claimed.

In the accompanying drawing, forming a part of this specification, Figure 1 is a side 20 view, partly sectional, showing the general construction of a stump-puller embodying our invention. Fig. 2 is a plan view of the same. Fig. 3 is a top view of the windlass drum. Fig. 4 is a bottom view of the 25 driver that engages the drum. Fig. 5 is a top view of the same. Fig. 6 is a fragmentary top view of the main frame and a spider revoluble in an annular bearing formed on said frame. Fig. 7 is a side view 30 of the sweep-clutch and a sectional view of the bearing-plate. Fig. 8 is a sectional view, showing the top of the clutch, and sections of the sweep-shank and the stud on which it turns. Fig. 9 is a fragmentary side view, 35 showing the mechanism for disengaging the sweep.

In the drawing, the numeral 1 designates the main frame which for convenience of transportation may be mounted on skids 2. 40 The frame is practically rectangular in form, preferably a single steel casting. Its top and bottom cross-bars serve as bearings for the windlass drum 3, on which winds the main cable 4. Its sides are of columnar 45 formation, partly for strength, and partly to serve, in the case of one of them, as a suitable means for the attachment of the main cable terminal, it being understood that the cable passes out to a sheave (not 50 shown) anchored to some stable support, and thence returns to the windlass. The peculiar attachment of this terminal is adapted to steady the whole machine, and prevent its tipping, whatever may be the 55 position of the cable winding on the windlass. It will be seen that the cable has a

looped, double connection with the side of the frame, near the top and bottom thereof, thus giving the cable a central pull on the frame, whether the cable be winding near 60 the top or bottom, or at any intermediate point. For this purpose the side column 5 is provided with flanged seats 6 to receive the loops of the cable, the lower flanges being considerably extended, as shown at 7, 65 to prevent the cable from slipping down and out of place. The anchoring cable 8 connects with the flanged part 10 of the opposite column by a sheave-block 11.

In the central hub 12 of the bottom cross-bar is rigidly secured a stud 13 extending up through a large hole in the upper cross-bar and to some distance above the frame. On this stud is mounted revolubly the driver 14 for the windlass drum 3, which is cored to 70 receive it. At the top and bottom the hole in the drum is made angular, as shown at 15 and 16, to receive similarly formed portions of the driver, 17 and 18, respectively. Above the angular shoulder 17 the driver is 80 extended upwardly in cylindrical form, and terminates in a series of clutch teeth or jaws 19. The cylindrical part is journaled in the large hole in the upper cross-bar, as shown. Above the driver is mounted the clutch 20, 85 having teeth to engage the teeth of the driver. This clutch is turned by the squared neck 21 of the sweep 22, and is free to slide up and down a limited distance thereon. The neck of the sweep turns on the upper 90 extension of the main stud, which gives a firm support therefor to hold it in proper horizontal position, and yet permit it to turn freely.

Provision is made for disengaging the 95 clutch 20, so that the drum may be turned independently of the sweep, for letting out or taking up slack in the cable. To upwardly extending flanges of the sweep is pivoted a forked lever 23, and to the short 100 arms of the lever connect links 24, whose lower ends connect with lugs 29 formed on the clutch flange. Referring to Fig. 9 it will be evident that the turning up of the lever will raise and release the clutch, which 105 remains engaged so long as the lever is depressed. To make this engagement positive at such time the lever is so formed that when depressed the link connections with the short arms of the lever are carried a little past the center, so that strains which would tend 110 to lift the clutch only lock the lever more

securely in position. The device is adapted for the easy release of the clutch, when desired, the releasing pull being in line with the neck of the sweep, and equally applied at each side.

The inside of the annular flange 25 forms a bearing for a bearing-plate 26 in the nature of a spider or wheel. It is provided with a series of openings 27 to admit freely 10 the downwardly extending jaws of the clutch, which are sufficiently separated to straddle the spokes 32 of the bearing-wheel. The hub 30 is bored at 28 to fit neatly on the stud 13 and turn freely thereon. The 15 rim 31 fits neatly, but revolvably in the flange 25. It will be seen by reference to Fig. 1 that the clutch jaws engage the driver below this spider-like bearing.

This construction entirely obviates what 20 has hitherto been a serious difficulty connected with the operating of these stump-pullers. To secure the free turning of the drum when the sweep was disengaged, the drum was mounted by its driver on the long 25 stud which carried the sweep at its upper end. In practice it was found, however, that the overhanging weight of the sweep was sufficient to deflect the stud a little. This caused the drum and its driver to bind 30 so tightly in its bearings as to render it difficult or impossible to turn it by hand. It will be noted that the stud is now entirely independent of the driver, except at the lower end, the rest of the hole through 35 the driver being large enough so that the stud may bend considerably without touching it. This deflection of the stud, however, is prevented by the bearing-plate, which operating in a bearing independent of the 40 driver, holds the stud rigidly upright. There is thus nothing to prevent the clutch being very easily operated, and when it is 45 disengaged the drum may be easily turned by hand.

Having thus described our invention, we 45 claim:

1. In a stump-puller, the combination of 50 a main frame having in its upper portion a large bearing-hole, a stud secured in the lower part of the frame and projecting through said hole, a driver journaled on said stud and in said hole, and squared near its upper and lower ends, a drum fitting said 55 squared parts at top and bottom, a clutch engaging the driver, and a sweep engaging the clutch.

2. In a stump-puller, the combination of 60 a main frame having in its upper portion a large bearing-hole, a stud secured in the bottom part of the frame and rising through said hole, a driver journaled on said stud and inside said hole, and having upwardly disposed jaws, a drum engaging said driver, a sweep-head revoluble on the upper part of the stud, a clutch mounted slidably on the sweep-head and adapted to engage the driver, and means adapted to raise the clutch out of engagement with the driver.

3. In a stump-puller, the combination of 65 a main frame having in its upper portion a large bearing-hole, a stud secured in the bottom part of the frame and rising through said hole, a driver journaled on said stud and in said hole, a drum engaging said driver, a clutch adapted to engage the 70 driver, a sweep-head on which the clutch is slidably mounted, a forked lever straddling the sweep and fulcrumed thereon, and links connecting the short arms of the lever with the clutch, the lever being adapted to lock 75 the clutch in engagement when depressed.

4. In a stump-puller, the herein described drum-drive, comprising with said drum, a stud fixed at its lower end, a driver socketed in the drum, and having a lower journal 80 bearing on the stud and an upper bearing above the drum, a sweep-head having an elongated neck journaled on said stud and outwardly squared, a clutch fitted slidably 85 thereon, and means adapted to lift the clutch 90 for disengagement.

5. In a stump-puller, the combination with 95 the drum, its driver and a retaining frame having in its upper part a bearing-hole for the drum, of a stud fixed in the lower part of the frame and rising through the hole in the upper part of the frame, a larger bearing located above said bearing hole, a bearing-plate revoluble therein and on said stud, and suitably apertured to allow the 100 passage of clutch-jaws through it, a sweep-head revoluble on the upper part of the stud, and a clutch slidably thereon, with jaws adapted to pass through the bearing-plate and engage the driver.

In testimony whereof we affix our signatures in presence of two witnesses.

EDWARD W. LA PLANT.
ROY E. CHOATE.
